UNITED STATES PATENT OFFICE.

FRED G. VOGLER, OF NEW YORK, N. Y., ASSIGNOR TO HARRY BAMFORTH, OF NEW YORK, N. Y.

DESIGN FOR AN EMBLEM, AN ARTICLE OF MANUFACTURE.

53,755.

Specification for Design.

Patented Aug. 26, 1919.

Application filed December 30, 1918. Serial No. 268,989. Term of patent 3½ years.

To all whom it may concern:

Be it known that I, FRED G. VOGLER, a citizen of the United States, residing in the borough of Manhattan, city, county, and State of New York, have invented a new, original, and ornamental Design for an Emblem, an Article of Manufacture for Use on Flags, Pennants, Badges, Jewelry, and the like, of which the following is a specification, reference being had to the accompanying drawing, forming part thereof.

The drawing shows an emblem, an article

of manufacture, my new design in simple form, the distinctive feature being the representation of stars and stripes on the wings of the eagle.

I claim:

The herein shown ornamental design for an emblem, an article of manufacture.

FRED G. VOGLER.

Witnesses:

HARRY BAMFORTH,
GEO. WM. MIATT.
